GUN

Gladeon M. Barnes, Hastings, Mich.

Application January 5, 1934, Serial No. 705,387

11 Claims. (Cl. 89—43)

(Granted under the act of March 3, 1883, as
amended April 30, 1928; 370 O. G. 757)

The invention described herein may be manufactured and used by or for the government for governmental purposes, without the payment to me of any royalty thereon.

This invention relates to a gun in which a brake mechanism utilizes the compressive action and reaction of the gases of discharge to check recoil and restore the gun to battery.

The improvements are directed to a novel means for varying the length of recoil of the gun by changing the volume of the brake system. Auxiliary chambers are selectively included in or excluded from the system as the gun is moved in depression or elevation.

A novel method of lubrication is provided in which the lubricant is forced out of its container under the influence of inertia forces produced through firing the gun.

A further object of the invention is to provide an arrangement of a valve which is held open by inertia as the gun moves in recoil.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawings, wherein:

Fig. 1 is a longitudinal sectional view of the front part of the gun.

Fig. 1^a is a continuation of Fig. 1, showing the rear portion of the gun partly in section and partly in elevation.

Figs. 2 and 3 are sectional views on the respective lines of Fig. 1.

Fig. 4 is a sectional view on the line 4—4 of Fig. 3.

Fig. 5 is a sectional view on the line 5—5 of Fig. 1^a, and

Fig. 6 is a sectional view on the line 6—6 of Fig. 5.

Referring to Figs. 1 and 1^a there is shown a gun barrel 5 reciprocally mounted in a cradle 6 having trunnions 7 at its rear end whereby it is supported for movement in elevation on a carriage 8.

Secured to the muzzle of the gun barrel is a combined brake and gas collector including a casing 9 spaced radially from the end portion of the barrel and carrying baffles 10 for deflecting

gases rearwardly. A valve block 11 integral with the casing 9 is provided with a pair of inlet passages 12—12 establishing fluid communication between the casing 9 and a recoil cylinder 13 secured at its forward end to the block 11.

The inlet passages are similar and each one includes an offset portion 14 and a valve seat 15. A valve having its stem 16 slidably mounted in the block 11 is arranged with its head 17 forwardly of the valve seat 15 so that on recoil movement of the gun the force of inertia will tend to maintain the valve in the open position. The valve is normally held in the open position by means of a spring 18 confined between a nut 19 on the valve stem and a seat 20 which is formed by a flange on a tube 21 threadedly attached to the valve block. The valve stem 16 is provided with a number of grooves 22.

A lubricant container 23 carried on the rear side of the valve block is in communication with an upwardly inclined passage 24 in the block which leads to the valve stem. Upon recoil movement of the gun the lubricant under the influence of inertia is forced through the passage 24 and into the grooves 22 of the valve stem, and in addition to lubricating the stem serves as a seal to prevent leakage of gas flowing from the gun to the recoil cylinder. When the gun is at rest the lubricant drains back into its container. In the case of a 3 inch gun, a pound of oil confined in a cylinder having a cross-sectional area of one inch produces a pressure when the gun is fired of about 100 pounds per square inch.

The recoil cylinder 13 movable with the gun barrel, cooperates with a piston head 25 on a hollow piston rod 26 fixed to the cradle 6. On the rear end of the recoil cylinder is an annular lubricant container 27 embracing the piston rod. The front end of the container is formed of an adapter 28 by means of which the container is attached to the recoil cylinder while the rear end is formed by a ring 29. The container has a fluid tight and sliding fit on the piston rod and to this end packings 30—31 held in place by glands 32 and 33 are interposed respectively between the front and rear ends of the container and the piston rod. A passage 34 in the adapter 28 serves as an inlet and outlet for the lubricant, enabling it to be forced out of the container by inertia to lubricate the contacting surfaces of the piston and recoil cylinder and to be returned to the container by the action of the piston head during counterrecoil of the recoil cylinder. The lubricant also finds its way to grooves 35 in the piston head where it serves as

a gas seal. A filling aperture 36 and a draining aperture 37 are respectively provided in the upper and lower portions of the container.

Referring to Figs. 3 and 4 the piston head 25 is hollow and includes a sleeve 38 of reduced diameter on its forward end. A valve 39 slidably mounted in the sleeve by means of guides 40 has a head 41 on its rear end for engaging a valve seat 42 on the rear end of the sleeve. A cross-piece 43 in the piston head serves to limit rearward movement of the valve. The valve is formed with a longitudinal passage 44 and a communicating radial passage 45 positioned in rear of the valve head 41. A plug 46 in the front end of the longitudinal passage 44 is provided with a passage 47 dimensioned to control the rate of exhaust of the gases and therefore the velocity of the gun in counterrecoil.

Referring to Figs. 1a, 5, and 6 the rear portion 20 of the piston comprises concentric cylinders 48 and 49, respectively of smaller and greater diameter than the hollow rod 26. The annular space defined by the cylinders 48 and 49 is divided into a plurality of chambers by partitions 25 50, in the present instance two chambers 51 and 52 being provided. The rear portions of the cylinders 48 and 49 are connected by a valve block 53.

The rear end of the inner cylinder 48 is provided with a pair of ports 54—54 which are in communication with passage 55—55 formed in the valve block and leading to the chambers 51—52. Each passage 55 is formed with a valve seat 56. The passage 55 leading to the chamber 51 may be closed by a short valve 57 and the passage leading to the chamber 52 may be closed by a long valve 58. The valves 57 and 58 are identical except as to their length and are provided respectively with pistons 59 and 60. The piston 59 works in a chamber 61 and the piston 40 60 works in a chamber 62.

The valve block is provided with an axial passage 63 in which a slidably mounted valve 64 is constrained against rotation by means of a pin or shoe 65 riding in a groove 66 in the valve block. The rear end of the valve 64 is provided externally with threads 67 engaging with threads 68 provided internally on a shaft 69. The shaft is mounted for rotation in a bearing consisting 50 of an end plate 70 for the valve block and a gland 71 secured to the end plate. The shaft is held against axial displacement by means of a flange 72 confined between the end plate and gland. A gear wheel 73 on the outer end of the 55 shaft is driven by gearing 74 meshing with an arcuate rack 75 fixed to the carriage 8 so that as the cradle 6 is elevated or depressed the shaft will be rotated to translate the valve 64.

The valve 64 is formed with an axial passage 60 66 and has a radial port 77 leading therefrom to an annular chamber 78 provided by necking the valve.

The passage 63 in the valve block is in communication with the chamber 61 by means of ports 79 and 80 the former being positioned forwardly of the piston 59 and the latter positioned rearwardly thereof. The passage 63 is also in communication with the chamber 62 by means of ports 81 and 82 positioned respectively in front 70 of and in rear of the piston 60. The corresponding ports 79—81 and 80—82 on opposite sides of the passage 63 are spaced from each other longitudinally with respect to the valve 64 so that they are successively covered and uncovered by 75 the valve 64.

The valves 57 and 58 are normally maintained in their forward position against the valve seats 56 in order to close the passages 55 relative to the ports 54.

The means for closing the valves 57 and 58 are identical. Each of the valves includes a rod 83 on its rear end passing through a plug 84 threaded in the valve block 53 and closing the valve chamber. A tubular extension 85 on the plug 84 houses and seats a spring 86 that acts 10 on a head 87 on the rear end of the rod 83.

When the valves 57 and 58 are closed the pistons 59 and 60 are directly in rear of the respective ports 79 and 81. When the valve 64 is in its rearmost position uncovering both of the ports 79 and 81 as seen in Fig. 5 the pressure fluid or gas in the system flows through the ports 79 and 81 and acting on the pistons forces the valves 57 and 58 to the rear or open position. The chambers 51 and 52 are now in communication with the cylinder 48 of the piston rod and the volume of the system is at a maximum. In this adjustment of the valves the gun barrel which is at zero elevation has its greatest length of recoil.

When the valve 64 is in its foremost position indicated by the dotted line in Fig. 5, it covers both of the ports 79 and 81. The pressure fluid or gas flowing through the axial passage 76 in the valve 64, the port 77, chamber 78, and ports 80 and 82, enters the chambers 61 and 62 in rear of the pistons 59 and 60 and holds the valves 57 and 58 in the closed position. In this position of adjustment with both of the chambers 51 and 52 closed off the volume of the system is at a minimum and the gun barrel will have a short length of recoil.

When the valve 64 is in an intermediate position the chamber 51 will be open and the chamber 52 will be closed.

The variation in the volume of the system is dependent on the adjustment of the valve 64 which is controlled through the gearing 73—74 as the gun is moved in elevation or depression. While in the present instance the volume of the 45 system and the corresponding length of recoil has been divided into three parts or steps, it is readily apparent that the chambers 51 and 52 may be sub-divided and additional valves provided.

When the gun is fired, a portion of the rapidly expanding gases of discharge are deflected by the baffles 10 and delivered past the valves 16—17 to the recoil cylinder 13. A part of the energy of recoil of the gun barrel is counteracted by the 55 forward pressure exerted on the vanes. The gases delivered to the cylinder 13 open the valve 39 in the piston head and flow into the piston rod and then act to open the valves 57 and 58 or hold them in closed position depending on the adjustment of the valve 64.

When the pressure in the cylinder 13 and piston rod 26—48 exceeds the rapidly decreasing pressure in the bore of the gun the valves 16—17 are closed. The gases confined in the cylinder and piston rod will be compressed as the forward end of the cylinder approaches the stationary piston head and will act to yieldingly check the recoil of the gun and then react to move the gun in counterrecoil.

During the counterrecoil stroke of the gun and cylinder 13, the volume of the cylinder is increasing and the pressure therein is correspondingly decreasing so that it is less than the pressure in rear of the piston head. As a consequence the 75

gases flow forwardly, close the valve 39 in the piston head and taking the path through the passages 45-44-41 in the valve act on the front end of the cylinder 13 to move the gun into battery.

5 The relative position of the cylinder and piston may be reversed.

I claim:

1. In a gun, a support, a cradle trunnioned on the support, a gun reciprocally mounted on the cradle, a recoil mechanism utilizing the compressive action and reaction of the gases of discharge to check recoil and restore the gun to battery and including a recoil cylinder movable with the gun and a hollow piston fixed to the cradle and in communication with the recoil cylinder, a cylinder on the rear end of the piston and radially spaced therefrom, a partition dividing the space to provide a plurality of chambers, a fluid passage between the piston and each chamber, a valve normally closing each passage and having a piston, ports for conducting gases to the front and rear of the piston of each valve, corresponding ports being longitudinally spaced, a control valve for successively covering and uncovering said ports, and means operable on elevation of the cradle for positioning the control valve.

10 2. In a gun, a support, a cradle trunnioned on the support, a gun reciprocally mounted on the cradle, a recoil mechanism utilizing the compressive action and reaction of the gases of discharge to check recoil and restore the gun to battery and including a recoil cylinder movable with the gun and a hollow piston fixed to the cradle and in communication with the recoil cylinder, a cylinder on the rear end of the piston and radially spaced therefrom, a partition dividing the space to provide a plurality of chambers, a fluid passage between the piston and each chamber, a valve normally closing each passage and having a piston, ports for conducting gases to the front and rear of the piston of each valve, corresponding ports being longitudinally spaced, a control valve for successively covering and uncovering said ports.

15 30 35 40 45

3. In a gun, a support, a cradle trunnioned on the support, a gun reciprocally mounted on the cradle, a recoil mechanism utilizing the compressive action and reaction of the gases of discharge to check recoil and restore the gun to battery and including a recoil cylinder movable with the gun and a hollow piston fixed to the cradle and in communication with the recoil cylinder, a cylinder on the rear end of the piston and radially spaced therefrom, a partition dividing the space to provide a plurality of chambers, a fluid passage between the piston and each chamber, and means adjusted upon elevation of the cradle for selectively controlling the opening and closing of the fluid passages to the chambers.

4. In a gun, a support, a cradle trunnioned on the support, a gun reciprocally mounted on the cradle, a recoil mechanism utilizing the compressive action and reaction of the gases of discharge to check recoil and restore the gun to battery and including a recoil cylinder movable with the gun and a hollow piston fixed to the cradle and in communication with the recoil cylinder, a cylinder on the rear end of the piston and radially spaced therefrom, a partition dividing the space to provide a plurality of chambers, a fluid passage between the piston and each chamber, and means for selectively controlling the

opening and closing of the fluid passages to the chambers.

5. In a gun, a support, a cradle trunnioned on the support, a gun reciprocally mounted on the cradle, a recoil mechanism utilizing the compressive action and reaction of the gases of discharge to check recoil and restore the gun to battery and including a recoil cylinder movable with the gun and a hollow piston fixed to the cradle and in communication with the recoil cylinder, auxiliary chambers at the rear of the piston, a fluid passage between the piston and each chamber, a valve normally closing each passage and having a piston, ports for conducting gases to the front and rear of the piston of each valve, corresponding ports being longitudinally spaced, a control valve for successively covering and uncovering said ports, and means operable on elevation of the cradle for positioning the control valve.

10 15 20 25 30 35 40 45 50

6. In a gun, a support, a cradle trunnioned on the support, a gun reciprocally mounted on the cradle, a recoil mechanism utilizing the compressive action and reaction of the gases of discharge to check recoil and restore the gun to battery and including a recoil cylinder movable with the gun and a hollow piston fixed to the cradle and in communication with the recoil cylinder, auxiliary chambers at the rear of the piston, a fluid passage between the piston and each chamber, a valve normally closing each passage and having a piston, ports for conducting gases to the front and rear of the piston of each valve, corresponding ports being longitudinally spaced, a control valve for successively covering and uncovering said ports.

39 45 50 55 60 65 70

7. In a gun, a support, a cradle trunnioned on the support, a gun reciprocally mounted on the cradle, a recoil mechanism utilizing the compressive action and reaction of the gases of discharge to check recoil and restore the gun to battery and including a recoil cylinder movable with the gun and a hollow piston fixed to the cradle and in communication with the recoil cylinder, auxiliary chambers at the rear of the piston, a fluid passage between the piston and each chamber, and means adjusted upon elevation of the cradle for selectively controlling the opening and closing of the fluid passages to the chambers.

40 45 50 55 60 65 70 75

8. In a gun, a support, a cradle trunnioned on the support, a gun reciprocally mounted on the cradle, a recoil mechanism utilizing the compressive action and reaction of the gases of discharge to check recoil and restore the gun to battery and including a recoil cylinder movable with the gun and a hollow piston fixed to the cradle and in communication with the recoil cylinder, auxiliary chambers at the rear of the piston, a fluid passage between the piston and each chamber, and means for selectively controlling the opening and closing of the fluid passages to the chambers.

65 70 75 80 85 90

9. In a gun, a recoil system including a primary pressure fluid chamber, auxiliary pressure fluid chambers for increasing the volume of the system, fluid passages between the primary and each of the auxiliary chambers, and means adjusted upon elevation of the gun for selectively controlling the opening and closing of the fluid passages to the auxiliary chambers.

10. In a gun, a recoil system including a primary pressure fluid chamber, auxiliary pressure fluid chambers for increasing the volume of the system, fluid passages between the primary and

75 80 85 90 95

each of the auxiliary chambers, and means for selectively controlling the opening and closing of the fluid passages to the auxiliary chambers.

11. In a gun, a reciprocally mounted gun barrel, a brake mechanism for the barrel, a gas passage establishing communication between the gun barrel and brake mechanism, a valve for

opening and closing the passage and mounted for sliding movement substantially parallel to the axis of reciprocation of the barrel, said valve having forward movement in opening the passage whereby the force of inertia tends to open 5 the valve upon recoil of the gun barrel.

GLADEON M. BARNES.
